UNITED STATES PATENT OFFICE.

GEORGE H. GREIMANN, OF GARNEE, IOWA, ASSIGNOR TO GREIMANN DITCHER COMPANY, OF GARNER, IOWA, A CORPORATION OF IOWA.

CLEANING DEVICE FOR EXCAVATORS.

1,406,849.

Specification of Letters Patent. Patented Feb. 14, 1922.

Application filed November 5, 1920. Serial No. 421,899.

To all whom it may concern:

Be it known that I, GEORGE H. GREIMANN, a citizen of the United States, residing at Garner, in the county of Hancock and State 5 of Iowa, have invented certain new and useful Improvements in Cleaning Devices for Excavators; and I do hereby declare the following to be a full, clear, and exact description of the invention, such as will enable 10 others skilled in the art to which it appertains to make and use the same.

My present invention has for its object to provide an improved cleaning device for cleaning or scraping the spades, buckets or 15 excavating blades of excavators of the type, for example, disclosed and claimed in my prior Patent No. 1,287,675, of date December 17, 1918, entitled "Excavator." The invention is illustrated in the accompanying 20 drawings, wherein like characters indicate like parts throughout the several views.

Referring to the drawings:

Fig. 1 is a fragmentary side elevation showing the cleaner and illustrating the action thereof;

Fig. 2 is a horizontal section on the irregular line 2—2 of Fig. 1, some of the parts being left in full; and

Fig. 3 is a view looking at the cleaner in 30 the direction of the arrow marked adjacent to Fig. 2, some of the parts being sectioned on the line 3—3 of said Fig. 2.

Of the parts of the excavator, in so far as they are shown, the numeral 4 indicates an 35 upright framework to which an oblique boom-supporting beam or frame 5 is rigidly secured. The numeral 6 indicates a power driven shaft journaled in suitable bearings on the beam 5 and carrying a polygonal, 40 preferably a hexagonal, wheel 7, over which runs a sprocket chain or link belt 8. Certain of the links of the chain 8 carry outstanding arms 9, to the flanged outer end of which excavating devices, herein designated as spades 10, are rigidly secured. 45 These spades or excavating devices 10 are curved on such lines that they are approximately concentric to the axis of the shaft 6 while passing around said shaft. The 50 spade-carrying arms 9, transversely of the

plane of movement, are narrow, but, in the plane of movement, have sufficient extension to give the desired strength.

The cleaner comprises two preferably triangular cleaner blades 11 and two spring 55 arms 12, to the free ends of which arms, said cleaner blades 11 are rigidly secured. Said arms 12 are preferably curved throughout and, at their outer ends, are formed with helical or spiral coils, the ends of which are 60 rigidly secured to anchor blocks 13. These anchor blocks 13, as shown by nut-equipped bolts 14, are pivoted to supporting plates 15 that are bolted or otherwise rigidly secured to upright members of the frame 4. 65 At points offset from the pivot bolt 14, nut-equipped bolts 16 are passed through perforations in the anchor blocks 13 and through segmental slots 17 in the bearing plates 15. The slots 17 and bolts 16 afford means for 70 adjusting the tension under which the spring arms 12 will be yieldingly pressed outward. The outward movements of the free ends of the arms 12 and of the blades 11 that are attached thereto are limited by 75 stop devices, shown as afforded by short chains 18 that are adjustably anchored to brackets 19 on a post of the upright frame 4. As shown, the chain 18 is connected to an eye-bolt 20 that is equipped with a nut 80 21. A coiled spring 22, placed around the eye-bolt 20, is compressed between the bracket 19 and a washer held by the nut 21. The two spring arms 12 are extended obliquely inward and stand preferably at an 85 angle to each other of little more than ninety degrees. When properly adjusted, the cleaner blades 11 will be in a position to nearly, but not quite, engage the spades that are moved past the same by the carrying chain 90 8, and there is sufficient space left between said blades 11 to permit the flat arms 9 to pass between the same. Thus, the cleaner or scraper blades are positioned to keep the spades or excavating devices clean, but they 95 are so supported that they will readily yield substantially in all directions to permit the blades 11 to clear stones or other hard objects that may be picked up and moved with the spades in the excavating action. For 100

example, the peculiar spring formation of the arms will permit the blades 11 to move forward with the spades or to move laterally to clear an object or to move radially inward or toward the shaft 6. Otherwise stated, the spring arms support the cleaner blades 11 normally in position to clean the spades or excavating devices, but under excessive force applied to the blades, said arms do not hold the blades for any particular line of receding movement but hold them free to partake of any direction of movement that will enable the blades to move easily and quickly escape the contact.

15 The coiled springs 22 serve as shock absorbers to prevent jars when the cleaner blades and arms have been moved out of position and then suddenly released and allowed to fly back to working or normal positions.

20 The nut 21, on the eye-bolt 20, permits adjustments of the stop chain so as to set the cleaner blades 11 to work as closely as practical to the excavating spades and to the arms 9.

25 What I claim is:

1. The combination with an endless carrier and spades or excavating blades carried thereby, of a spade cleaning device comprising a spring arm equipped with a cleaning blade at one end and spirally coiled and anchored at its other end so that said cleaner blade is capable of approximately universal yielding movement under pressure in the cleaning action.

2. The combination with an endless carrier and spades or excavating blades carried thereby, of a spade cleaning device comprising a spring arm equipped with a cleaning blade at one end and spirally coiled and anchored at its other end so that said cleaner blade is capable of approximately universal yielding movement under pressure in the cleaning action, and a stop device limiting the forward movement of said arm and blade under the spring tension in said arm.

3. The combination with an endless carrier and spades or excavating blades carried thereby, of a spade cleaning device comprising a spring arm equipped with a cleaning blade at one end and spirally coiled and anchored at its other end so that said cleaner blade is capable of approximately universal yielding movement under pressure in the cleaning action, and an adjustable anchor to which the coiled end of said spring arm is secured.

4. The combination with an endless excavator belt having outwardly projecting arms, of excavating spades or blades rigidly secured to the outer ends of said arms and projecting on both sides thereof, and a pair of spring arms having spirally coiled anchored ends and provided at their

free ends with anchor blades spaced to permit the spade-equipped arms to pass therebetween and positioned to operate adjacent to the inner surfaces of the passing spades.

5. The combination with an endless excavator belt having outwardly projecting arms, of excavating spades or blades rigidly secured to the outer ends of said arms and projecting on both sides thereof, a pair of spring arms having spirally coiled anchored ends and provided at their free ends with anchor blades spaced to permit the spade-equipped arms to pass therebetween and positioned to operate adjacent to the inner surfaces of the passing spades, and adjustable anchors to which the coiled ends of said spring arms are secured.

6. The combination with an endless excavator belt having outwardly projecting arms, of excavating spades or blades rigidly secured to the outer ends of said arms and projecting on both sides thereof, a pair of spring arms having spirally coiled anchored ends and provided at their free ends with anchor blades spaced to permit the spade-equipped arms to pass therebetween and positioned to operate adjacent to the inner surfaces of the passing spades, and flexible stops for limiting the movements of said spring arms in the direction in which they are impelled by their own spring action.

7. The combination with an endless excavator belt having outwardly projecting arms, of excavating spades or blades rigidly secured to the outer ends of said arms and projecting on both sides thereof, a pair of spring arms having spirally coiled anchored ends and provided at their free ends with anchor blades spaced to permit the spade-equipped arms to pass therebetween and positioned to operate adjacent to the inner surfaces of the passing spades, said spring arms being set in outwardly converging arrangement, and stops for limiting the movements of said arms in the direction in which they are impelled by their own spring actions.

8. The combination with spades or excavating blades and means for moving the same on an endless course, of a spade-cleaning device comprising an arm that is anchored at one end and is made of spring metal so that it will yield, and a cleaning blade secured to the free end of said arm and positioned to clean the spades as they pass the same.

9. The combination with spades or excavating blades and means for moving the same on an endless course, of a spade-cleaning device comprising an arm that is anchored at one end and is made of spring metal so that it will yield, and a cleaning blade secured to the free end of said arm and positioned to clean the spades as they pass the same, said spring arm being curved

so that it is capable of approximately universal yielding movements under pressure in the cleaning action.

10. The combination with spades or excavating blades and means for moving the same on an endless course, said spades having centrally located supporting arms, of a pair of curved spring arms anchored at

one end and provided at their free ends with cleaning blades that are positioned to 10 clean the spades as they move past the same and are spaced to clear the supporting arms of said spades.

In testimony whereof I affix my signature.

GEORGE H. GREIMANN.
